S. SALL

TRACTION MAT

Filed April 10, 1924

Inventor
SAM SALL

By Harry DeWallace.

Attorney

UNITED STATES PATENT OFFICE.

SAM SALL, OF SYRACUSE, NEW YORK.

TRACTION MAT.

Application filed April 10, 1924. Serial No. 705,487.

To all whom it may concern:

Be it known that I, SAM SALL, a citizen of the United States, residing at Syracuse, in the county of Onondaga and State of New York, have invented certain new and useful Improvements in Traction Mats, of which the following is a specification.

This invention relates to improvements in traction mats, designed to be conveniently carried by an automobile, and which may be readily and effectively employed for extricating the power-driven wheels of the vehicle from mud-holes, loose sand, or marshy sections of a road, without requiring jacking-up or otherwise hoisting the vehicle wheels.

A particular object of the invention is to provide a simple, light and strong device of the class, which is flexible throughout, and therefore may be readily and properly applied to a rut, and which also readily conforms itself to conditions of the road ahead of the wheel; one end of the device being equipped with a woven chain section, which insures positive and unfailing traction at the start of the extricating operations. A further object is to provide a succession of transverse angle irons closely and evenly linked to each other, which are arranged to provide a temporary corduroy, for supporting the vehicle, immediately following its initial forward movement over the chain section, until the wheel is free from the mud or sand. And a further object is to provide a traction mat that may be constructed from commercial angle-iron and chain stock, at slight expense, and which may be rolled into a compact bundle and readily stowed away in a corner of the tool-box, or beneath one of the vehicle seats.

I attain these objects by the means set forth in the detailed description which follows, and as illustrated by the accompanying drawing, in which—

Figure 1 is a top plan view of the complete device, extended ready for use. Fig. 2 is an edge view of the same. Fig. 3 is a view illustrating the application of the mat to a mired wheel. And Fig. 4 is a view showing the mat rolled up for storage, when idle.

In the drawing, 2 represents conventionally a wheel of an automobile, which is shown mired in a marshy section of a road or mud-hole 3.

My improved traction mat consists mainly of a plurality of angle irons 4, all of which

are preferably the same length and are disposed parallel to each other. The angle irons 4 are preferably regularly spaced apart, and are held in relatively close order, so that the whole of the main body of the mat is rendered flexible, by means of two series of links 5, each of said links being loosely inserted through corresponding perforations 6, which are located near the adjacent edges of the irons 4, as best seen in Fig. 1. By this construction and arrangement of the parts 4 and 5, the main body of the mat is adapted to readily conform to almost any condition of a road or rut, and the device may also be readily rolled into a compact bundle, as shown in Fig. 4, for conveniently carrying and storing the same. The iron members 4 are preferably disposed so that the apexes 4' of the members face upwardly, and these relatively sharp corners tend to bite or sink transversely into the elastic material of the tire shoes, and thereby afford the very best and surest tractive means for extricating the wheels, as 2, from loose sand, mud, or other miry condition of the roads. The close spacing of the members 4 is provided expressly for insuring the positive and constant engagement by the wheel of two or more of the angular ribs 4, thereby improving the tractive effect of the mat. Owing to the rigidity of the members 4, and the pitch of their angles 4^a, the wheels do not always take hold of the barred portion of the mat, as readily as desired. To overcome this difficulty, in a simple and novel manner, I provide at one end of the mat proper, a woven section comprising a plurality of parallel longitudinally arranged chains 8, of equal length, whose forward end links are loosely attached to the end iron 4, by means of a number of perforations 8', while the opposite ends of said chains are suitably connected and spaced, by a transverse chain 8^a. This chain section, is usually first inserted beneath the mired wheel, as shown in Fig. 3, by means of a stick, or other suitable ramming implement, and the said section being flexible throughout, may be readily applied under conditions, wherein the stiff and more bulky members 4 could not be so readily disposed. Furthermore, the chain section readily conforms to and tends to embrace the rounding tread of the tire, and owing to the arrangement and shape of the links 8^b, provides the requisite traction to instantly start the extrication of

the wheel. As the wheel 2 progresses over the chain section, the weight of the vehicle tends to hold the mat from slipping until the tire engages the sharp ridges 4' of the irons. By this arrangement, there is no danger of the mat creeping or becoming distorted by the rotation of the wheel, and thereby frustrating the work.

Obviously, owing to the loose arrangement 10 of the links 5, the mat may be flexed laterally (not shown), so as to provide a curved path for the wheel 2; and changes may be made in the construction and arrangement 15 of the parts of the device, without departing from the scope of the invention, as defined by the appended claims.

Having thus described my invention, what I claim, is—

1. A traction mat comprising a plurality 20 of parallel transversely disposed angle irons, single links connecting the opposite ends of the adjacent edges of the said irons and evenly spacing the same, and a woven chain section projecting from one end of 25 the angle-iron body adapted to provide initial traction for a mired vehicle wheel.
2. A traction mat comprising a succession of closely spaced cross members formed from

angle iron flexibly connected by means of similar single links, one of the end members being provided with a row of perforations, and a plurality of longitudinally disposed chains having their corresponding ends inserted through said perforations, and having their opposite ends connected and spaced by 35 a transverse chain, the said chain section adapted to be rammed beneath a mired wheel for affording tractive support for the wheel until the latter engages the rigid cross members. 40

3. A traction mat including a plurality of transversely disposed angle members whose apexes face upwardly, said members being closely and evenly spaced and flexibly connected by single links which engage corresponding perforations formed in the adjacent edges of the members, one of the end members being provided near its free edge with a row of perforations, a series of parallel longitudinally arranged chains of 45 50 equal length engaging said perforations, and a transverse chain connecting and spacing the free ends of the longitudinal chains.

In testimony whereof I affix my signature.

SAM SALL.
